PERISCOPE STRUCTURE

Frederick L. Chaimson, Washington, D. C.

Application June 9, 1950, Serial No. 167,089

2 Claims. (Cl. 88—68)

1

This invention relates to periscopes, and more particularly to a periscope of the type adapted to be formed from a folded cardboard blank.

A main object of the invention is to provide a novel and improved periscope which is very simple in construction, which is easy to form, and which is provided with improved means for retaining the mirrors of the periscope in accurately parallel position.

A further object of the invention is to provide an improved periscope which is very inexpensive to manufacture, which may be made from a single cardboard blank, and which requires no special fastening means for securing the mirrors of the periscope inside the housing thereof.

Further objects and advantages of the invention will become apparent from the following description and claims, and from the accompanying drawings, wherein:

Figure 1 is a front elevational view of an improved periscope constructed in accordance with the present invention;

Figure 2 is a horizontal cross-sectional view taken on line 2—2 of Figure 1;

Figure 3 is a longitudinal cross-sectional view taken on the line 3—3 of Figure 1;

Figure 4 is a top plan view of a blank employed to form the periscope of Figures 1 to 3.

Referring to the drawings, the periscope is designated generally at 11 and comprises a rectangular, elongated housing formed of cardboard or other suitable foldable material, the housing comprising the front and rear walls 12 and 13, the side walls 14 and 15, a bottom cover shown at 16, and a top cover shown at 17. The front wall 12 is formed near its lower end with a substantially rectangular, large aperture 17', and secured in the lower end of the housing facing said aperture is an inclined mirror 18, said mirror being rectangular in shape. The top margin of the mirror is secured beneath a pair of inwardly struck tabs 19, 19 formed in the lower portion of the rear wall 13, and the lower edge of the mirror 18 abuts the inside surface of the bottom front corner of the housing, as shown in Figure 3. The rear wall 13 is formed adjacent its top end with a large, substantially rectangular aperture 20, and secured in the top end of the housing is a mirror 21 which is arranged parallel to the mirror 18. The lower margin of the mirror 21 is secured behind a pair of inwardly struck tabs 22, 22 formed in the upper portion of the front wall 12, the top edge of the mirror 21 being in abutment with the upper rear corner of the housing.

In using the device, the viewer holds the peri-

2

scope in a substantially vertical position and looks through the lower aperture 17', whereby he may observe images transmitted to the mirror 18 from the mirror 21.

Figure 4 illustrates one form of cardboard blank which may be employed to construct the periscope housing or box, above described. The blank comprises four sections which are shaped to define the respective front and rear walls 12 and 13 and the respective side walls 14 and 15. The sections 12, 14, 13 and 15 are arranged in side by side abutting relation and interconnected with each other along abutting side edges by fold lines 30, 31 and 32 respectively, the sections being foldable upon each other along said fold lines to form a four sided open ended enclosure. A tab 23 is positioned adjacent the non-abutting side of the outermost section or section 12 and is interconnected to said side by and foldable along a fold line 33, a face of the tab 23 having a coating of adhesive for securing of the nonabutting side of the other outermost section or section 15 thereto. A first flap 24 is arranged longitudinally of and adjacent one end of the outermost section 15 and has one end connected to the one end of the section 12 by a fold line 34, the flap 24 being foldable along the fold line 34 to close and provide a cover 16 for one of the open ends or bottom of the enclosure. A first auxiliary flap 24' is arranged longitudinally of and adjacent the other end of the first flap 24 and is interconnected to the other end of the flap 24 by a fold line 35, the flap 24' being foldable along the fold line 35 to engage the inner face of the section 13 of the enclosure. Arranged longitudinally of and adjacent the end of the section or section 13 which abuts the other of the outermost of the sections or section 15 opposite the one end of the innermost one of the sections or section 12, is a second flap 36, the flap 36 having one end interconnected to one end of the section 13 by a fold line 37 and foldable along the latter line to close and provide a second cover 17 for the other of the open ends or top of the enclosure. A secondary auxiliary flap 38 is arranged longitudinally of and adjacent the other end of the second flap 36 and is interconnected to the other end of the flap 36 by a fold line 39, the flap 38 being foldable along the fold line 39 to engage the inner face of the section 12 of the enclosure and form a four walled box with closed ends. The section 12 adjacent the flap 24 is provided with a viewing opening 17' and the section 13 adjacent the flap 36 is likewise provided with a similar viewing opening 20. Adjacent the other end of each of sections 12 and 13

are a pair of tongues 22 and 19 respectively, the tongues 22 and 19 being interconnected to and foldable upon the sections 12 and 13 to form an anchor for the mirrors 21 and 18 when the latter mirrors are supported in the box contiguous to the openings 20 and 17.

Opposed flaps 25 and 26 project longitudinally from the ends of the section 14 intermediate the outermost section 12 and the section 13 abutting the other of the outermost sections or section 15 and of the other outermost of the sections or section 15, each pair of flaps 25 and 26 being interconnected by fold lines 40 and 41 respectively to said sections 14 and 15, the adjacent flaps of the pair of flaps 25 and 26 when folded being in engagement with the covers 16 and 17.

While a specific embodiment of a periscope and blank for forming the periscope housing have been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. An article of manufacture for use in producing a periscope structure, said structure comprising an open ended collapsible rectangular tube having four elongated sections interconnected by fold lines along their abutting longitudinal edges so that said tube may be collapsed into a substantially flattened condition, a flap foldable inwardly from one end edge of one of said sections and closing one end of said tube, another flap foldable inwardly from one end edge of the section parallel to said one section and closing the opposite end of said tube, each section of a parallel pair of sections having a rectangular opening adjacent one end thereof and a plurality of laterally spaced tabs spaced inwardly from the opposite end thereof with the opening and tabs of one of said sections disposed opposite the tabs and opening, respectively, of the other of said sections, the tabs of each of said sections being folded interiorly of said tube along a line substantially coplanar with the innermost transverse edge of the opening of the other of said sections to form an anchor for one edge of a mirror which is adapted to be disposed diagonally between said parallel pair of sections, and each foldable flap providing an anchor for the opposite edge of the mirror when disposed between said parallel pair of sections.

2. An article of manufacture for use in producing a periscope structure, said structure com-

prising four elongated sections arranged in side by side abutting relation and interconnected by fold lines along their longitudinal edges, securing means connecting the non-abutting longitudinal edges of the outermost sections together by a fold line to thereby form a foldable blank of an open ended rectangular tube in collapsed condition, a flap adapted to be folded inwardly from one end edge of said one of said sections and to close one end of said tube when said blank has been shifted to its open condition, another flap adapted to be folded inwardly from one end edge of the section alternately disposed to said one section and to close the opposite end of said tube when said blank has been shifted to its open condition, each section of an alternate pair of sections having a rectangular opening adjacent one end thereof and a plurality of laterally spaced tabs spaced inwardly from the opposite end thereof with the opening end tabs of one of said sections disposed in reverse relation with respect to the tabs and opening, respectively, of the other of said sections, the tabs of each of said sections being adapted to be folded interiorly of said tube along a line substantially coplanar with the innermost transverse edge of the opening of the other of said sections when the blank has been shifted to its open condition to form an anchor for one edge of a mirror which is adapted to be disposed diagonally between said alternate sections, and each foldable flap when the blank has been shifted to its open position providing an anchor for the opposite edge of the mirror when disposed between said alternate sections.

FREDERICK L. CHAIMSON.
